WILLIAM MEYER, OF CHICAGO, ILLINOIS.

FACIAL TREATMENT METHOD AND MEANS.

Application filed June 12, 1925. Serial No. 36,602.

My invention relates to an improved facial treatment method and means, and more particularly to an improved method of and means for washing, cleansing, stimulating 5 and toning the face and the like.

Water is well recognized as the universal washing and cleansing agent. As the temperature of the water is increased, it softens and penetrates more quickly until, as it 10 reaches the boiling point, it breaks down tissue and cooks it.

The application of hot towels by barbers and masseurs is well known. Continuous use of this method is objectionable, because 15 it will cause the facial tissues to relax and sag. With the heating element in contact with the liquid, it is necessary to apply sufficient heat to form steam and cause same to issue therefrom. It is not possible to form 20 water vapor and project or cause same to circulate upon the face because the body of liquid will cause immediate condensation and there will be no vapor reaching the face. To sufficiently heat the entire body of 25 liquid to avoid this, requires considerable heat and steaming of the liquid. The application of steam to the face is objectionable for the same reasons as pointed out in connection with hot towels, but even more pronounced, if anything. Furthermore, nobody enjoys the scalding hot sensation produced, nor do they enjoy breathing air permeated with steam to a degree where it may 30 be questioned whether or not it is safe or may have dire consequences on the respiratory 35 organs.

My invention contemplates an improved facial treatment method which comprises forming a liquid vapor and directing the liquid vapor upon the face. There is a great 40 difference between steam and vapor. Steam is produced at 212 degrees F. while water vapor may be produced at temperatures much lower than that. Much less heat is 45 therefore required and what is more important, the objectionable results of steam upon the face are avoided. The vaporization may be at as low a temperature as will cause proper dissolution of the impurities and dislodgment of foreign matter imbedded in 50 the face and a thorough cleansing of the pores at temperatures but little above normal may be secured.

My invention further contemplates directing radiant energy upon the face with the liquid vapor. This stimulates the glands to

proper activity and rejuvenates the face. The simultaneous application of the two thoroughly cleanses the pores and gives permanent tone to sagging, anemic, and even 60 painful muscles.

The source of radiant energy employed is preferably a suitable source of radiant heat and light such as a suitable incandescent or electric lamp. For the purpose of 65 forming the water vapor, I provide means which may be in the form of the wick-like element adapted to soak up the liquid and give off the vapor. This permits the heating element to be disposed out of contact with 70 the liquid to be vaporized and permits subjecting the liquid only partially at a time to the heating element, as in the general form of a film, so that the liquid may be vaporized at relatively low temperatures and so that 75 the liquid vapor will reach the face before condensing and without steaming.

The source of radiant energy may constitute the heating element, in which case the radiant heat and light will both act to vaporize the liquid, as desired. By projecting the radiant energy from said source upon the face as the face is subjected to the liquid vapor, a thorough cleansing, toning and stimulation is secured, and for the purpose of screening the ultra-red, actinic or other objectionable rays which will or may affect the eyes or have any other deleterious action, I provide a shield for screening same therefrom. This shield may comprise coloring the bulb of the electric light where an electric light is employed, or it may be in the form of a separate shield. When in the form of a coloring, its color may be according to the particular rays which it is desired to screen out, or where a separate shield is employed, it may be formed to act in a similar manner. A breather for supplying fresh air to the patron may also be provided, in which case tenseness is avoided 100 and perfect relaxation secured. A sanitary removable breather is contemplated for this purpose and it may be adapted for supplying fresh air through the nostrils, mouth, or both. The device may also include a supporting standard for supporting it in proper position for use, preferably suspended in oblique position, although this may, of course, be varied as desired.

In order to acquaint those skilled in the 110 art with the nature and method of my invention and with the manner of constructing

and operating a device embodying the invention, I shall now describe in connection with the accompanying drawings, the method of the invention and means for carrying it out.

5 In the accompanying drawings:—

Fig. 1 is a side elevational view of a device embodying my invention showing in dotted lines the application of the face thereto;

10 Fig. 2 is a vertical section longitudinally through the device;

Fig. 3 is a transverse section taken on the line 3—3 of Fig. 2;

15 Fig. 4 is an isometric view showing the heating element; also the wick-like element and means supporting the wick-like element;

Fig. 5 is a plan view of one form of breather;

20 Fig. 6 is an end view of the same; and Fig. 7 is an isometric view of a modified form of breather.

The device which I have selected for illustration comprises a shell 5 of generally oblong cross-section and preferably having 25 a rounded top 6 and a rounded bottom 8. This shell 5 may be formed of sheet metal or other suitable material and has an open end 10 surrounding which the adjacent edge of the shell is rolled back to form a bead 12. 30 The opposite end of the shell 5 is closed by a bottom or end closure 14, having a lateral flange 15 surrounding the adjacent edge of the shell, and the end or bottom closure 14 may be soldered, welded or otherwise joined 35 to the adjacent end of the shell to attach it firmly thereto and provide a tight joint therewith. The end closure 14 may have a vent opening 14'. Inwardly from the open end 10 of the shell 5 is a vertical partition 16 40 extending up from the bottom of the shell entirely thereacross. This partition 16 may be soldered or welded in place, or it may be otherwise formed in the shell and its function will hereinafter be apparent.

45 For supporting the device in operative position, I provide a standard 18 having a base 20, the legs of which may be provided with rollers 21. Carried at its lower end by the base 20, is an upright post 23, which is 50 preferably tubular and telescoping therein is an auxiliary post 24. The post 24 has sliding movement into and out of the post 23 for the purpose of adjusting the height or vertical positioning of the device and it may 55 be secured in any desired adjusted position, as by means of a set screw 25.

The post 24 has a lateral arm 26 at the forward or outer end of which is an eye 28. The top 6 of the shell 5 has secured thereto, 60 as by means of screws 29, a bracket 30, and this bracket 30 carries a hook 32 which is adapted to be hooked into the eye 28 to suspend the device from the lateral arm 26 of the support. The anchored end of the 65 hook 32 extends through an opening in the

bracket 30 and is headed at its lower or inner end to anchor it in the bracket, the opening in the bracket through which this hook extends, being preferably slightly larger than the hook, to permit at least a limited 70 fulcrumming action of the hook in the bracket. To further properly hold the device in place, a flexible suspension link 34, as for example a suitable chain secured at its upper end to the lateral arm 26 of the support 75 and hooked or otherwise attached to the closed end of the shell 5, supports the closed end of the shell 5 and prevents turning or lateral displacement of the shell out of proper operative position about the hook 32. 80 The suspension link 34 is preferably slightly longer than the hook 32, so that the shell 5 will, when suspended from the arm 26, be held in oblique position with its open end inclined upwardly, as shown. The purpose 85 of this will be hereinafter apparent.

Fitted and suitably secured in an opening centrally in the bottom or end 14 of the shell 5, is an electric connector 40. This electric connector 40 may take any suitable or preferred form, and it may, of course, be mounted as desired. Within the shell 5 it has means for mounting and electrically connecting the heating element or source of radiant energy into the desired circuit. This 90 means is preferably in the form of a standard "Edison" socket 42. Outwardly of the shell 95 the conductors 43 for connecting the device into the desired electric circuit enter the electric connector 40 and are electrically connected to suitable contact means therein. Also, preferably outwardly of the shell the connector 40 is provided with suitable switch means, such as, for example, in the form of a pull chain 45 for turning the current for 100 the device on or off, as desired.

In the embodiment of the invention illustrated, a suitable electric or incandescent lamp 50 constitutes the source of radiant energy. This lamp or light 50 may have the 110 usual plug or base connector 52 adapted to be screwed into the socket 42 to mount the light and bring it into electrical connection with the contacts of the connector 40 so that when the current to the device is turned on 115 by the switch means 45, the lamp 50 will be placed in circuit with the conductors 43.

The support for the wick-like element of the device comprises a plate 54 having a central opening 55 through which the base 120 of the lamp 50 extends in making connection with the socket 42. The plate 54 is provided with a multiplicity of relatively closely related perforations 56 and peripherally it conforms generally to the interior contour 125 of the shell 5. Integral lugs struck up laterally from spaced points about the periphery of the plate 54, engage the interior of the shell 5 and hold the plate 54 properly positioned therein.

Carried by the plate 54 is a frame for the wick-like element. This frame comprises a ring 60 disposed in operative position adjacent the free end of the light 50. A plurality of rods 62 secured at their outer ends to the ring 60 extend longitudinally and are turned in at 64 at the reduced or base end of the lamp 50. The base ends of these rods 62 are turned out laterally parallel the plate 54 at 65 and these base ends 65 are suitably secured to the plate 54 about the opening 55 as by soldering or welding them to the plate 54.

The wick-like element is designated at 70 and it comprises a strip of material adapted to draw up the water or other liquid and subject it partially at a time in what I term here a "film" to the lamp 50. By the term "film" I, of course, include the saturated strip or any other analogous or equivalent partial subjection of the water or other liquid to the heating element. The wick-like element may be formed of a porous absorbent and preferably non-conducting substance such as woven asbestos or the like. I find loosely woven asbestos highly desirable, in that it will soak up the liquid and give off the gases vaporized by the heating element. Also, it will not become scorched or burned nor its functioning impaired by subjection to the heat of the lamp 50. Woven wool or other suitable material may, of course, be employed, but in such cases I believe that treating of said material with means for preventing its scorching or burning is preferable.

The wick-like element 70 is folded intermediate its ends about the frame, thereby surrounding or encasing the lamp 50. It may be sewed or otherwise suitably attached to the frame, and at the base end of the lamp 50 it is preferably drawn in about the lamp 50 as by means of a cord 72 for closing off that end and preventing material escape of radiant energy rearwardly. Longitudinally along the bottom of the lamp 50, the opposite sides of the wick-like element 70 are brought together and secured as by means of the cord 72, and an additional knotted cord 73, or in any other suitable manner. The strip from which the wick-like element is formed, is preferably sufficiently long to leave flaps 75 which hang down upon the bottom 8 and into the body of water 76 which is placed therein.

For the purpose of supplying fresh air to the patron, the device is preferably provided with a breather 80. This breather 80 comprises a hollow nipple 81 opening through the bottom 8 of the shell 5 and projecting internally therefrom. Fitting over or mounted on said nipple 81 is a relatively short rubber hose or flexible tube 82, and the breather element 83 is adapted for removable attachment to the free end of this

tube or hose 82. The breather element 83 has at one end a tubular or hollow stem for insertion into the tube 82, and at its opposite end it may have a pair of hollow stems 85 (Figs. 5 and 6) for insertion into the nostrils 70 of the patron as shown in Fig. 1. Alternatively, the breather element may have a single hollow stem 86 at its free end as shown in Fig. 7, for insertion into the mouth or a combination element for cooperation 75 with both mouth and nostrils is contemplated.

The breather 85 is preferably of glass or other material, which may be conveniently washed or cleansed. It is removable from the tube 82 for this purpose and a high degree of sanitation is thereby provided. Of course, it may be made of any other suitable material that may be conveniently cleansed, or the provision of individual breathers of paper material or the like adapted for individual use and to then be thrown away or discarded, is contemplated. The conductor means 48 may have at its free end a suitable connector 86 for electrical connection with 80 any standard "Edison" service outlet or for connection with any other desired circuit or source of current.

In operation, the face indicated at 90 in dotted lines in Fig. 1 is disposed adjacent the open end 10 of the shell 5. The breather stems 85 of the breather element 83 are inserted into the nostrils, as indicated in Fig. 1, or into the mouth or both, as pointed out. A large glass or two of water or other suitable liquid, is poured into the shell 5, assuming generally the position indicated at 76 in Fig. 2. A towel or other suitable cover indicated in dotted lines at 92 in Fig. 1, is then arranged over the head, as shown, and the current to the source of radiant energy is turned on as by means of the pull chain switch 45. For the purpose of securing the towel or cover over the open end of the shell 5, an annular or continuous coiled spring 95 100 is provided about the shell 5. The adjacent edge of the towel or cover 92 is arranged externally about the open end of the shell, and the spring 95 is sprung or snapped or arranged over this marginal edge and holds 105 the cover firmly in place over the open end of the shell.

The wick-like element is preferably first dipped or saturated in the water or liquid. The flaps 75 thereupon soak up the water or liquid indicated at 76, it being understood that these flaps extend in operation down into the body of liquid 76, and by capillary action the water or other liquid travels up through the wick-like element 70 and around the lamp 50 in what I have already termed here as a generally film-like formation. This subjects the liquid partially at a time to the radiant energy and heat of the lamp 50. The radiant heat and light emitted by the 110

lamp 50 both act to vaporize the liquid, and when the face is under the cover 92 there is a perfect shower of small water particles and vapor emitted or projected upon the face to cleanse and treat the same. The lamp 50 being out of direct contact with the body of liquid 76, but little current is required and steaming of the liquid is avoided, also it is thereby possible to vaporize the liquid and have the water vapor reach the face before it condenses.

The radiant energy emitted by the lamp 50 which includes the radiant heat and such radiant light as is not screened out, is projected simultaneously upon the face, stimulating the glands and pores and giving an effective toning and rejuvenation to the face. At the same time, the breather 80 supplies fresh air to the patron from without the shell 5 so that there is no tenseness but perfect relaxation.

For the purpose of screening from the face the ultra-red, actinic or other objectionable rays which will or may affect the eyes or have any other deleterious action upon the face or eyes, I provide a shield for screening said rays therefrom. This shield may consist in coloring the glass 98 or providing a coating thereon. The color employed may be according to the particular rays which it is desired to screen out. I find that by coloring the bulb of the lamp 50 red or coating it therewith, the desired deleterious rays are screened out and an exceedingly stimulating action is produced upon the face. The particular manner of forming this shield or screen may, of course, be varied, and a screen or shield in the form of a separate shield independent of the lamp, is contemplated.

I do not intend, of course, to be limited to the precise details shown and described. For example, the source of radiant energy may be other than an electric or incan-

descent lamp, and the manner of vaporizing the liquid and subjecting the face to the liquid vapors may be practiced with variations in the elements and combinations shown. There are no heater coils to burn out, automatic recondensation of the water vapor is attained, and the cost of operating is exceedingly low.

I claim:

1. In a device of the class described, an enclosing shell, a source of energy in said shell, means in said shell for subjecting the liquid to be vaporized to said source of energy, a member carrying said last means and cooperating peripherally with the interior of the shell to position said means therein, said shell being adapted to contain a liquid and said positioning member being perforate.

2. In a device of the character described, a shell open at one end for reception of a person's face, a source of heat and radiant energy adjacent the other end of the shell and means for supplying liquid to be vaporized to the heat and energy source in the form of a film surrounding said source and disposed closely adjacent but out of contact therewith, the end of said means toward the open end of the shell being open to permit unimpeded flow of light and heat rays together with vapor particles from the heat and energy source to the open end of the shell.

3. In a device of the character described, a shell open at one end, a source of heat and radiant energy adjacent the other end of the shell, a wick of absorbent material surrounding said heat and energy source, said wick being open at the end thereof towards the open end of the shell, and means for supplying liquid to the wick.

In witness whereof, I hereunto subscribe my name this 8th day of June, 1925.

WILLIAM MEYER.
